FREDERICK HARTT KNEVITT AND HENRY HERBERT HAZARD, OF LONDON, ENGLAND, ASSIGNORS TO FREDERICK HARTT KNEVITT.

Letters Patent No. 96,014, dated October 19, 1869.

IMPROVED WINDOW-SHUTTER AND BLIND.

The Schedule referred to in these Letters Patent and making part of the same

To all whom it may concern:

Be it known that we, FREDERICK HARTT KNEVITT and HENRY HERBERT HAZARD, both of London, England, have invented certain new and useful "Improvements in Shutters and Blinds for Windows, Doorways, and other Apertures, and the means for adjusting the same;" and we do hereby declare that the following is a full and exact description thereof, reference being had to the accompanying drawings, forming part of this specification.

Our improvements relate to shutters and blinds, which are composed of a number of parallel laths or slats jointed together, and arranged in such a manner that they may be coiled upon a roller, or otherwise raised, lowered, or moved across a window, doorway, or other aperture, to open and close the same.

The said improvements consist in the peculiar means whereby the laths or slats are "louvered" or adjusted angularly, to admit or exclude the light. The laths or slats are provided at one or both ends with two pins or projections. Each of these two pins or projections works in one part of a compound or double groove on the frame of the window, doorway, or other aperture. The said compound groove is so constructed that the distance between the two parts of the same may be increased or diminished, as desired, to open or close the slats or laths, the said laths being so connected or jointed together as to allow of their free division or action in "louvering;" and in order to keep the two parts of the groove always parallel with each other, we prefer to connect them by arms or links, in the same manner as an ordinary parallel rule; or the adjustable part or parts of the groove may be provided with studs, which work in curved slots or guideways. These slots allow the movable part to move, and keep it parallel with the fixed part as it is raised. We adjust the compound groove by means of levers, cords, toothed racks, and pinions, or by other convenient means. It will generally be found more advantageous to have one part of the said groove fixed and the other movable, but, if desired, both parts or channels of the double groove may be made adjustable.

The adjustment or "louvering" of the shutter or blind may be effected when the same is either entirely or partially drawn over the window, doorway, or other aperture, and the laths or slats will be held as firmly in the grooves when they are adjusted to any desired angle, as when fully closed or opened.

Our improved shutters or blinds may be constructed of metal or wood. We prefer to fix the pins or projections on a separate piece (or pieces) of iron or other metal, which is secured upon the end of the lath, but, if desired, in some cases, the said pins may be formed upon the lath itself. The said shutters may be arranged to coil upon a roller, or may be made to slide

vertically or horizontally, or otherwise, to open or close the window or other aperture, and may be operated in any convenient manner.

Description of the Drawings.

Figure 1 is a vertical section of a casement-window provided with one of our improved "louvering"-shutters, arranged to coil upon a roller or cylinder at the top of the said window.

Figures 2 and 3 represent sections of a portion of the said shutters, more clearly illustrating the means for "louvering" or adjusting the laths of the same.

Figure 4 is a back elevation, and

Figure 5, a horizontal section of similar parts of the said shutter.

Figs. 2, 3, 4, and 5, are drawn to an enlarged scale. Like letters indicate the same parts throughout the drawings.

A is the shutter, composed of the laths *a*, which may be of any desired dimensions, and formed of any suitable materials.

The compound or double groove *b* consists of the fixed part *b*¹ and adjustable part *b*², and the pins or studs *a*¹ *a*² are fitted to work freely in these grooves, as clearly shown in fig. 5.

The laths or slats *a* are of the usual form employed for coiling shutters, and, as shown in figs. 3 and 4, are connected at proper distances apart to strips *c* of webbing, or other suitable flexible material.

The laths are preferably connected to the webbing by strips of leather *c*, attached to the webbing by copper rivets.

The coiling-cylinder or roller *d* is mounted in the brackets *e*, which are attached to the under side of the lintel, and the said roller, as shown in fig. 1, is arranged above the window-frame in a convenient position to wind the shutter entirely above the window.

It is obviously necessary that the two parts, *b*¹ *b*², of the compound groove should be kept always parallel with each other, while, at the same time, they must be capable of easy adjustment from the position shown in fig. 2, to that in fig. 3, and vice versa, or to any intermediate position. For this purpose, we prefer to connect the two parts of the groove together by the arms or links *f*, which, as in an ordinary parallel rule, permit the free adjustment of the two sides, while keeping them always parallel with each other. We prefer to use three of these links *f* at each side of the shutter, as shown in fig. 1, but any convenient number may be used.

The "louvering" or adjustment of the said shutters, in the example illustrated in fig. 1, is effected by means of the segment or half pulley *g*, which is fitted to turn upon the pin *g*¹, fixed in the frame or other convenient portion of the structure, and which is jointed near its

periphery, by means of a pin, g^2 , to the adjustable part b^2 of the compound groove. When the said segment is in the position shown in fig. 1, the two parts of the compound groove lie close together, and the laths or slats a are closed, but if the said segment is turned to a right angle, or to any intermediate angle with this position, the movable part b^2 of the compound groove will be separated from the fixed part b^1 , and the laths will be opened more or less, according to the extent of such separation.

A cord, h , connected to the upper end of the segment g , is carried over the pulley i , and extended downward into a convenient position to allow the adjustment or "louvering" of the shutter to be effected thereby.

The lintels k , frame j , sill k' , and other parts of the window may be constructed in any suitable manner, but the soffit l is fitted to slide in the frame, to allow access to the roller d , and to facilitate the mounting and removal of the same.

It will thus be seen that the "louvering" of the shutter or blind can be accomplished with equal facility in all positions of the shutter, that is to say, whether the shutter is partially coiled upon the roller or is let completely down to secure or close the window, and that the firmness or stability of the shutter is not in any degree affected by the "louvering," as the pins a^1 a^2 are always kept within the two parts b^1 b^2 of the compound groove, which guide and support the laths in as perfect a manner as though both of the said parts or sides were immovable.

Thus the operations of coiling and "louvering" are each effected without interfering with each other, or rendering the shutter less convenient with regard to either function, and we are enabled to provide a shutter or blind which combines the security of an ordinary coiling shutter with the comfort and convenience of a Venetian blind.

Our "louvering" compound groove may be applied

to an ordinary outside Venetian blind, which is thus made to serve the purposes of a shutter and blind.

The raising and lowering of the blind may be effected in the ordinary manner by means of a cord, while the "louvering" or adjustment of the laths is effected by the means hereinbefore described.

We prefer generally to use an arrangement by which the varying weight upon the lifting-cord is balanced, or nearly so, by a compensating weight.

This method of "louvering" a Venetian blind will be found much superior to the old method of adjustment by cords.

This modification of our improvements may be readily applied to the windows of any existing dwelling-house, and in other cases, where it is not convenient to form a recess or chamber in the wall above the window-frame, the blind in such cases being hung below the top of the frame, in the ordinary manner.

It is obvious that either of the modifications of our invention herein described, may be applied to either a casement or a sash-window.

What we claim as our invention, and desire to secure by Letters Patent, is—

1. The two parallel grooved parts, b^1 and b^2 , constructed and operating together as herein described, in combination with the laths or slats of the revolving shutter or blind A, the said laths or slats having pins or studs fitted to work in the grooves of said parts, all substantially as herein set forth.

2. Effecting the separation and approximation of the two parts b^1 b^2 , of the compound groove by the segment g , arranged and operating in combination with the said parts, and provided with a cord or other means of adjustment, substantially as set forth.

FREDERICK HARTT KNEVITT. [L. S.]
HENRY HERBERT HAZARD. [L. S.]
